PROTECTIVE SPRAY FIRE NOZZLE

John N. Martin, Wendover, Utah

Application April 24, 1947, Serial No. 743,520

7 Claims. (Cl. 299—141)

1

This invention relates to a protective spray fire nozzle, and more particularly a nozzle for connection to a fire hose whereby a fireman holding a nozzle and directing its stream is protected by a curtain of atomized water particles or other fire extinguishing fluid.

Among the principal objects of the invention are to provide:

(a) A nozzle that is simple, efficient and relatively inexpensive.

(b) A nozzle so constructed that workmanship of a high degree enters into its manufacture without making its cost excessive.

(c) A nozzle that is durable, that does not easily get out of order, and that is especially guarded against the entrance of grit or other objectionable substances.

Other important objects will become apparent during the progress of the following description.

In general, fire nozzles with protective spray features are known, but do not possess the unique features which are outstanding in the device of the invention.

In the accompanying drawing which illustrates one embodiment of the invention,

Fig. 1 represents a longitudinal center section taken on the line 1—1 in Fig. 2;

Fig. 2, a rear elevation;

Fig. 3, a transverse section taken on the line 3—3 in Fig. 1;

Fig. 4, a fragmentary portion of Fig. 1 enclosed by the broken loop at 4 in Fig. 1, but showing a detail of somewhat different construction, drawn to an enlarged scale;

Fig. 5, an enlargement of substantially the portion enclosed by the broken line 5 in Fig. 1; and,

Fig. 6, a front elevation indicating the nozzle in actual operation, this figure being drawn to a reduced scale.

Referring to the drawing, the numeral 10 denotes the nozzle in general, and comprises a main body portion forming a barrel 11 to which is attached a front or tip portion 12. The barrel 11 has a taper bore 13 within which is concentrically fixed a sleeve 14, the wall of which is preferably of uniform thickness and follows in general the taper of the body 11. Advantageously the sleeve 14 is removable from the barrel 11, but normally is held in the fixed position therein by means of exterior ribs 15 that merge into a reinforcing end collar 16, both the ribs and the collar being preferably integral with the sleeve 14. The entire sleeve structure may be fastened in the barrel by any suitable means,

2

for example, screws 17, that in the present instance serve an additional purpose presently to be described. The advantage of making the sleeve 14 removable from the barrel includes the fact that the barrel can be bored out smoothly and the exterior surfaces of the sleeve be smoothed off perfectly, so that there is no roughness to be encountered by the flowing water that runs in the direction of the arrows in Fig. 1 through longitudinal passages 18.

The tapering bore 19 of the nozzle extends through its sleeve 14 at substantially a uniform taper from the back of the nozzle to the front of the tip 12, thereby offering a minimum obstruction or retardation to the passage of the main stream of the water that is directed into the fire. The passages 18 are at least partially defined by the successive ribs 15 and constitute auxiliary conduits to conduct water streams to the fog curtain, spray forming apertures at 20, 21 and 22, Figs. 1 and 5.

The conduits 18 at their discharge terminals direct the auxiliary water streams along streamlined surfaces 23 into an annular passage 24 formed largely in a ring-like fitting 25 that is held in place by the screws 17 hereinbefore mentioned. From the annular passage 24 the water is forced through the apertures 20, 21 and 22 to form the aforesaid fog curtain, the said apertures 20 to 22 being spaced radially around the ring fitting 25.

It is desirable that relief holes 26 be provided to establish communication between the auxiliary conduits 18 and the main stream of water flowing through the tapered bore 19. In order to assure a watertight joint between the ring fitting 25 and the outside of the barrel 11, circumferential gaskets 27 may be provided.

Mounted on the outside of the barrel 11, contiguous to the fitting 25, is a retractile sleeve 28 that serves as a closure or valve for controlling the action of the fog spray. This sleeve has two principal positions, one, the rearmost, shown in Fig. 1, in full lines, where the spray apertures 20, 21 and 22 are wholly uncovered, and another position, the foremost, indicated by the dotted lines 29, where the spray apertures are entirely closed. The back and forth movement of the sleeve valve 28 in this instance is effected by means of the threaded portion 30 that engages a correspondingly threaded portion 31 on the barrel 11.

The spray ring 25 has its outer surface tapered rearwardly as at 32, to form a seat for the sleeve valve when closed, the latter having a coopera-

tively tapered portion 33. The outside surface 34 of the sleeve valve is either knurled (not shown) or is provided with other well known means (not shown) to prevent slipping in the hands of a person operating the nozzle.

The unique construction of the nozzle as hereinbefore described makes it possible to provide means for preventing any clogging of the spray apertures 20, 21 and 22 because of foreign particles that are likely to accompany a stream of water. Such clog-preventing means in the present showing comprise metal wire screens placed at the stream entrance of the nozzle barrel. Examples of screens are shown at 35 in Figs. 1 and 2, and at 36 in Fig. 4. In Figs. 1 and 2 the screens are shown as lying approximately in the plane 37 of the stream entrance, while in Fig. 4, the screens are inclined with respect to the plane 37. In either case the effect of the incoming stream of water is to wash the surface of the screens clear of any foreign particles that may momentarily lodge thereon. However, in the case of the inclined screen surfaces, this clearing tendency of the stream is considerably increased. The screens 35 and 36 are held in place by any suitable means, for illustration, soldering or brazing the edges thereof to the contacting portions of the barrel and its tapered sleeve 14.

At 38 is shown a gasket that makes a watertight joint against the usual outlet fitting (not shown) of a fire hose.

In Figs. 1 and 5 the sprays 41 emerging from the apertures 21, are directed slightly outwardly with reference to a plane passing through these apertures at right angles to the longitudinal axis of the nozzle. At the same time the sprays 40 and 42 coming through the respective apertures 20 and 22 are directed so as to intersect each other as well as to intersect the sprays 41, the points of intersection being determined by the particular angularity of the respective apertures. An example of the intersecting points is indicated at 43. The purpose of causing the respective sprays to intersect one another is to thoroughly atomize the jets of water in transit and thereby greatly enhance their effectiveness.

It is to be observed in Fig. 1, the inside of the muzzle of retractile sleeve 28 is tapered, as indicated, for illustration, at 39. The effect of this tapered surface 39 is to deflect forwardly, successively, all three sprays 40, 41 and 42, away from a person holding the nozzle, when the sleeve 28 is moved forwardly. The forward travel of the sleeve gradually consolidates the plurality of sprays and brings about a still different spraying result from point to point until the final closing off of all the sprays. Rearward travel reverses the action.

Any nozzle is subject to the cutting action of water under pressure passing through its bore, the ensuing wear being a factor that shortens considerably the useful life of the entire usual nozzle structure.

It is to be observed that the tapered sleeve 14 forms a renewable lining for the nozzle shell of the invention, whereby a perfectly new nozzle is obtainable at a fraction of the first cost of the entire nozzle.

By means of the invention a stock of the interchangeably renewable linings can be kept on hand, and a virtually new nozzle be quickly made up, by unsoldering the screens 35 or 36, and resoldering them in place. Obviously, the invention is not necessarily restricted to fire nozzles.

While a specific embodiment of the invention

is herein shown and described, the scope of the invention is limited only by the following claims.

What is claimed is:

1. A nozzle comprising a barrel having a tapered bore; a lining having a plurality of radially spaced and longitudinally extending ribs conforming to said tapered bore and defining auxiliary conduits terminating in exit openings through and arranged circumferentially of said barrel; a spray ring encircling said exit openings of said barrel; and fastening means extending through said spray ring, said barrel, and said lining, for holding spray ring, barrel, and lining fixed relatively one to another.

2. A nozzle according to claim 1, wherein is included a shut-off sleeve movably encircling said spray ring and adapted to be seated thereon.

3. A protective spray fire nozzle, comprising a shell having a smooth bore axially therethrough; a separable sleeve lining defining a main conduit, said sleeve lining extending throughout the greater part of the length of said shell and having a plurality of substantially radial ribs spaced apart circumferentially and extending exteriorly thereof, the outer surfaces of said ribs conforming substantially to the bore of said shell so as to at least partially define auxiliary conduits having respective entrances arranged circumferentially about the entrance to said main conduit and respective exits directed laterally of said main conduit circumferentially of and adjacent the exit of said main conduit; laterally directed orifices defined by said shell and arranged in registry with the respective exits of said auxiliary conduits; spray means disposed across said orifices; and an annular collar formed adjacent the exit end of said sleeve lining at the said exits of the auxiliary conduits, said annular collar having concavely curved transition surfaces registering with the respective exits of the auxiliary conduits and directed to streamline the passage of liquid through said shell orifices.

4. A protective spray nozzle, comprising a shell structure having a smooth bore; a separable sleeve lining defining a main conduit, said sleeve lining extending throughout the greater part of the length of said shell structure and being equipped with integral, exterior ribs configurated to said bore in order that spaces between said ribs define, at least partially, auxiliary conduits leading to the front of said nozzle; side outlet spray means adjacent the front of said shell and in flow communication with said auxiliary conduit whereby liquid flowing through said auxiliary conduits is formed into a protective spray curtain surrounding said nozzle; and relief passages providing communication between said main conduit and said auxiliary conduits.

5. A protective spray nozzle, comprising a shell having a smooth bore axially therethrough; a separable sleeve lining defining a main conduit, said sleeve lining extending throughout the greater part of the length of said shell and having a plurality of substantially radial ribs spaced apart circumferentially and extending exteriorly thereof, the outer surfaces of said ribs conforming substantially to the bore of said shell so as to at least partially define auxiliary conduits having respective entrances arranged circumferentially about the entrance to said main conduit and respective exits directed laterally of said main conduit circumferentially of and adjacent the exit of said main conduit; laterally directed orifices defined by said shell and arranged in registry with the respective exits of said auxiliary con-

duits; and relief passages providing communication between said main conduit and said auxiliary conduits.

6. A protective spray nozzle, comprising a shell having a smooth bore axially therethrough; a separable sleeve lining defining a main conduit, said sleeve lining extending throughout the greater part of the length of said shell and having a plurality of substantially radial ribs spaced apart circumferentially and extending exteriorly thereof, the outer surfaces of said ribs conforming substantially to the bore of said shell so as to at least partially define auxiliary conduits having respective entrances arranged circumferentially about the entrance to said main conduit and respective exits directed laterally of said main conduit circumferentially of and adjacent the exit of said main conduit; laterally directed orifices defined by said shell and arranged in registry with the respective exits of said auxiliary conduits; an annular collar formed adjacent the exit end of said sleeve lining at the said exits of the auxiliary conduits, said annular collar having concavely curved transition surfaces registering with the respective exits of the auxiliary conduits and directed to streamline the passage of liquid through said shell orifices; a spray ring encircling said shell at the location of said orifices, and having spray-forming apertures in registry with said orifices; and screws threaded through said spray ring, said shell, and said annular collar, to hold said parts in rigidly assembled relationship, said screws having their heads exposed exteriorly of said spray ring for ease in disassembly.

7. A protective spray nozzle, comprising a shell having a smooth bore axially therethrough; a separable sleeve lining defining a main conduit, said sleeve lining extending throughout the

5 greater part of the length of said shell and having a plurality of substantially radial ribs spaced apart circumferentially and extending exteriorly thereof, the outer surfaces of said ribs conforming substantially to the bore of said shell so as to at least partially define auxiliary conduits having respective entrances arranged circumferentially about the entrance to said main conduit and respective exits directed laterally of said main conduit circumferentially of and adjacent the exit of said main conduit; and laterally directed orifices defined by said shell and arranged in registry with the respective exits of said auxiliary conduits said shell having a discharge end portion of smaller bore than the bore of the remainder of the shell, thereby providing a shoulder internally of the shell and intermediate the length thereof, said sleeve lining fitting snugly within the larger bore portion of said shell with its discharge end seating against said shoulder, and the main conduit of said sleeve lining leading into the said smaller bore portion of the shell.
